WATER-CONTROL SYSTEM FOR MACHINES
FOR WASHING DRINKING VESSELS

Walter F. Ohme and Ray C. Stephan, Minneapolis, Minn., assignors to North Star Specialty & Manufacturing Company, Minneapolis, Minn., a corporation of Minnesota

Original application August 23, 1934, Serial No. 741,078. Divided and this application October 7, 1936, Serial No. 104,474

5 Claims. (Cl. 141—3)

Our invention relates to machines for washing drinking vessels and particularly to the water control system therefor.

An object of the invention resides in providing a system by means of which all of the functions of the machine may be readily controlled.

Another object of the invention resides in providing a machine utilizing both hot and cold water and in which both the hot and cold water may be simultaneously turned on or shut off.

A still further object of the invention resides in providing a shut off valve mechanism for the machine utilizing two valve seats and valve heads cooperating therewith and a single operating member for simultaneously moving said valve heads into or out of engagement with said valve seats.

Another object of the invention resides in providing separate constant pressure regulating valves for the hot and cold water whereby the required pressure for both the hot and cold water sprays may be accurately maintained.

An object of the invention resides in providing a control valve whereby either hot or cold water may be delivered to one set of sprays.

A feature of the invention resides in providing a tray with a revolute rack disposed above the same and in spaced relation thereto and in arranging the constant pressure regulating valve and the control valve as well as certain of the sprays within said space.

An object of the invention resides in constructing the parts so as to require a minimum height whereby the rack can be disposed in close proximity to the tray.

Other objects reside in the novel combination of parts and in the arrangement of the valves and in the specific construction of the same as disclosed in the accompanying specification and drawings.

In the drawings:

Fig. 1 is a medial elevational sectional view of a machine for washing drinking vessels and illustrating an embodiment of our invention.

Fig. 2 is a plan sectional view taken on line 2—2 of Fig. 1 with portions thereof broken away to show the construction of other portions thereof.

Fig. 3 is a fragmentary plan sectional view taken substantially on line 3—3 of Fig. 1 and drawn to a larger scale.

Fig. 4 is an elevational sectional view taken on line 4—4 of Fig. 3.

Fig. 5 is an elevational sectional view taken on line 5—5 of Fig. 3.

This application for patent is a division of our copending application for patent for Machine for washing drinking vessels, Serial Number 741,078, filed August 23, 1934.

Our invention is particularly adapted for use in conjunction with a machine for washing drinking vessels and the same has been illustrated as applied thereto. Since certain details of construction of the machine do not form any part of the instant invention, only so much of the machine as will be needed to explain the instant invention will be described, the original application being relied on for disclosure of the remainder of the machine.

The machine for washing drinking vessels herein illustrated comprises a housing which we have indicated in its entirety by the reference character A and in which our improved water control system is utilized. The washing mechanism of the invention comprises a revolute rack B which is driven through a water motor C. In addition thereto, a spraying device D is utilized which is adapted to spray hot and cold water on the drinking vessels carried by the rack as the same rotates past the sprays. The invention comprises a water control system E forming the subject matter of this invention and by means of which the flow of water to the spraying device D and the motor C can be regulated and by means of which the water may be maintained at predetermined pressures at the various sprays and motor. These various parts will now be more fully described.

The housing A consists of a tray 10 circular in form which is constructed with a bottom 11 having a rim 12 extending upwardly therefrom. The bottom 11 is preferably sloping toward the forward portion of the tray where a drain 13 is provided by means of which the water discharged into the housing may be removed from the device. At the outer margin of the bottom 11 is provided a ledge 14 which elevates the bottom 11 above the surface on which the machine rests. This ledge may, if desired, be formed in continuation of the rim 12 of said tray. The tray 10 is constructed as a casting or the same may be spun from sheet metal or constructed in any other suitable manner. The housing A further comprises a circular wall 15 which is secured to the rim of the tray 10 and extends upwardly therefrom. The lower edge of this wall rests in a recess 17 formed in said rim. The wall 15 is preferably attached to said rim through small bolts 16 which pass through suitable openings in both said rim and wall. Upon the upper end 55

of the wall 15 is placed a cover or closure 13 which is circular throughout the extent thereof. This closure is provided with a flange 20 which extends downwardly therefrom and which terminates at its lower end in a lip 21 by means of which the closure may be secured to the wall 15. This is accomplished through bolts 22 which pass jointly through said wall and lip the same as the bolts 16. The wall 15 is of lesser circular extent than a complete circle so that an opening 23 is provided at the front of the housing through which access may be had to the interior thereof and to the drinking vessels placed upon the rack B mounted therein.

15 The rack B consists of a table 24 which is constructed with a number of circularly disposed concentrically arranged rings 25, 27 and 28. These rings are connected together through radially extending bars 26 to form a reticulate structure on which the drinking vessels or other dishes to be washed may be placed. The rings 25, 27 and 28 and are bars 26 all lie in a common horizontal plane so as to form a suitable support for the drinking vessels. The outer ring 27 is provided with an upwardly extending flange 29 by means of which the drinking vessels are held upon the rack.

30 The table 24 is rotatably supported on a spider 31 which comprises a central tubular hub 32 connected to a circular flange 30 through radially extending arms 33. The hub of this spider has mounted in it ball bearings 34 and 35 which are disposed at the upper and lower ends thereof. In the center of the bottom 11 of tray 10 is provided a boss 36 which has secured to it through a set screw 37 an upwardly extending post 38. Post 38 is turned to receive the inner races of the two bearings 34 and 35. By means of the two bearings 34 and 35 the spider 31 is rotatably mounted. A cap 39 secured to the upper end of the hub 32 covers the bearings 34 and prevents the entry of water into said bearings from above. The table 24 rests upon arms 133 extending outwardly from the flange 30 of spider 31 and is centered with respect to the axis thereof through said flange.

45 The flange 30 similar to flange 29 extends upwardly above the surface of the table 24 to hold articles positioned thereon in place. To further serve this purpose a guard 229 is employed which is constructed from sheet metal bent in cylindrical form with a curvature substantially equal to the curvature of the flange 30. This guard is bolted to a mounting 230 by means of bolts 231 and may be easily removed when access into the interior of the machine is desired. Mounting 230 may be soldered or otherwise secured to the cover 18.

60 The water motor C and the power transmission associated therewith are illustrated in Figs. 1 and 2. This part of the invention includes a frame 40 which comprises two spaced parallel bearing plates 41 and 42 held in spaced relation through posts 43. These posts are riveted to the plate 42 and the plate 41 is secured to said posts through screws 44 threaded into said posts. In the two plates 41 and 42 are mounted two self-lubricating bearings 45 which are attached to said plates in any suitable manner. In the bearings 45 is rotatably mounted a shaft 50. Shaft 50 has attached to it a water wheel 51. This wheel is constructed from a sheet of metal which is arranged to form a back 52 which is cut at its outer periphery to provide a plurality of blades 53 extending substantially radially with respect to

the wheel. The shaft 50 drives another shaft 61 (Fig. 1) through a gear train 55 consisting of a number of arbors pivoted between the plates 41 and 42 and carrying intermeshing gears and pinions. Such construction forming no particular feature of the instant invention has not been shown in detail, applicant's original application for patent from which this application is divided being relied upon for disclosure thereof.

10 The shaft 61 is mounted for rotation in bearings formed in the two plates 41 and 42. The upper end of the said shaft projects above the plate 41 and has attached to it a friction pinion 62. This pinion comprises a core 63 on which a short section of a rubber tube 64 is applied, which tube is held in position on said core through a screw 65 threaded into said core. When the screw 65 is properly tightened, the tube 64 is held from movement and the pinion 62 functions in the desired manner.

15 The frame 40 is mounted for swinging movement relative to the bottom 11 of tray 10 in the following manner: Extending through the two plates 41 and 42 is a bolt 66 which is screwed into a boss 68 formed on the bottom 11. This bolt 20 supports the entire frame for swinging movement clear of the bottom 11. The frame 40 is urged outwardly through a tension spring 69 which is attached at one end to the plate 42 and at its other end to an angle member 70 serving as a 25 spring anchor. This angle member is attached to the bottom 11 in any suitable manner. The arms 33 of spider 31 are disposed toward the upper end of the flange 30 leaving the inner surface of said flange indicated at 73 unobstructed. 30 The portion of the flange 30 having the surface 73 constitutes a friction gear with which the friction pinion 62 may engage. This gear is designated in its entirety by the reference numeral 74. From an inspection of Fig. 2 it will be noted 40 that the pinion 62 is disposed at such an elevation as to engage the surface 73 of gear 74. Through the action of the spring 69 the pinion 62 is urged into frictional engagement with gear 74 and rotation of the rack B through the action of 45 the water motor C is procured.

The water motor C further includes a nozzle 75 which is connected with a source of supply of water and which is attached to a mounting 276. The nozzle 75 is fixed in position and is adapted 50 to direct a stream of water tangentially upon the blades 53 of the water wheel 51. This causes the wheel 51 to rotate and gear 62 is correspondingly rotated at a reduced rate of speed through the action of the gear train 55. Due to the fact that 55 the nozzle 75 is directly supported on the tray 11 a rigid pipe connection may be utilized for supplying water to the same and frame 40 on which the motor C is supported may swing freely to bring the pinion 62 into proper frictional engagement with its corresponding gear 74 without interference. This eliminates a flexible water pipe or flexible connection for the motor.

60 For the purpose of spraying water upon the glasses carried on the rack B the spraying device 65 D is used. This spraying device comprises two spray units 76 and 77. Spray unit 76 is disposed below the rack B and spray unit 77 is situated above said rack.

65 The spray unit 76 consists of an arcuate hollow manifold 78 which is constructed in two parts 57 and 58. The part 58 has three laterally extending branches 79, 80 and 81, and the two parts are connected together by means of a neck 82. In the middle of the neck 82 is provided a partition 83 75

which separates the two parts 57 and 58, providing two separate chambers 86 and 87 within the interior of the manifold. In the center of this partition is formed an opening 59 which extends along said partition. A heat insulating block 60 is disposed in this opening and retards the passage of heat from each of the parts 57 and 58 to the other. At suitable localities on the parts 57 and 58 of the manifold 78 and at the ends of the branches 79, 80 and 81 are provided sprays 88 which are adapted to direct fine sprays of water upwardly for the purpose of washing the vessels placed upon the rack B from beneath said vessels. These sprays and the sprays used with spray unit 15 77 are all constructed in the same manner and only one of said sprays will be described in detail which is best illustrated in Fig. 2.

On the manifold 78 at the required locality is provided an upwardly extending boss 84. This boss is constructed with an opening 85 passing through the same and communicating with the chamber 86 within the manifold. The boss 84 is threaded upon the exterior to receive a screw cap 90. Cap 90 is preferably formed from sheet metal and is constructed with a number of openings 91 through the same and through which the water passes in fine streams.

The upper spray unit 71 is constructed similarly to the unit 76, and since the same forms no feature of the invention said unit will not be described in detail. This unit is, however, constructed with two parts separated from one another and similar to the parts 57 and 58 of the unit 76.

35 The two spray units 76 and 77 are supported in the following manner: Attached to the rim 12 of tray 10 is an upright 96 formed of sheet metal which is bent to provide a back 97 and two outwardly extending flanges 98. This upright is bolted to a rectangular lug 99 formed on the said rim which projects inwardly into the pan 10. For this purpose a bolt 101 is employed which extends jointly through said lug, rim and upright. The flanges 98 engage this lug and hold the upright 40 in proper position. Upright 96 serves to support both the lower and upper spray units 76 and 77. The lower unit 76 is threaded to receive a machine screw 102 which passes through the said back 97 of the upright 96 and which is screwed 45 into unit 76. The unit 77 is similarly attached to the upper end of the upright 96 through another screw 103, which passes through the back 97 of said upright and which is threaded 50 into the neck 113 of the unit.

55 For the purpose of shutting off the hot and cold water to the sprays, a shut off valve mechanism 104 is employed which is mounted at the front of the tray 10. Upon the interior of the tray is provided a control valve 106, which is
60 disposed directly opposite the valve mechanism 104. The valve mechanism 104 includes a valve housing 105 and the control valve 106 includes a housing 107. These two housings are attached to the rim 12 of tray 10 in the following manner:
65 Upon the valve housing 107 are formed two lugs 108. Two cap screws 110 pass through these lugs and through a flattened portion 109 of the rim 12 and are threaded into the housing 105 of the valve mechanism 104. Gaskets 111 disposed between said housings and the flattened portion 109 of tray 10 form a tight connection between the various parts. The interior of the valve housing 105 is constructed to provide two valve chambers 112 and 113, which have passageways 114 and 115 leading therefrom. These passageways commu-

nicate with passageways 116 and 117 in the portion 109 of the tray 10. Said latter passageways in turn communicate with two passageways 118 and 119 in the valve housing 107, which will be subsequently more fully described. The housing 105 includes two threaded bosses 121 and 122, which have screwed upon the ends of the same caps 123 and 124, which have formed within them chambers 125 and 126. The said housing is tapped at 127 and 128 to receive two pipes 129 and 130, which furnish cold and hot water respectively to the device. Passageways 131 and 132 lead from the two pipes 129 and 130 to the chambers 125 and 126, and conduct the cold and hot water into said chambers.

For closing communication between the chambers 125 and 126 and the passageways 112 and 113, respectively, two valves 133 and 134 are employed. Inasmuch as both of these valves are identical in construction, only the valve 133 will be described in detail. This valve includes a valve stem 135, which is threaded to receive two nuts 136 and 137. Mounted upon the valve stem and between the two nuts 136 and 137, is a conical shaped rubber stopper 138, which is adapted to engage a seat 139 in the lug 121 at the end of the passageway 112. When the valve 133 is drawn inwardly, the stopper 138 engages the valve seat 139 and closes communication between the passageway 131 and the passageway 114.

For operating the two valves 133 and 134 a rotating shaft 141 is employed, which has formed on the end of it a head 142. This shaft is further provided with a shank 143, which is journaled in a bushing 144. Bushing 144 is adapted to screw into a threaded bore 145 in housing 105 and against a compression gasket 146, which encircles the shaft 141 and engages the upper surface of the head 142, thereby forming a tight joint between said shaft and housing. To remove any water which might leak past the gasket 146, an annular chamber 241 is formed in the bushing 144 which encircles the spindle 143. This chamber communicates through drilled openings 242 with another annular chamber 243 which is formed upon the exterior of the bushing 144. A passageway 244 through the valve housing 106 and rim 12 communicates with chamber 243 and conducts the leakage from the valve stem back into the tray 10 where the same is discharged from the device through drain 13. A handle 147 is secured to the outwardly protruding end of the shank 143 and serves as a means for rotating the shaft 141. Upon the underside of the head 142 are provided two depending pins 148 and 149, which are spaced from one another and are eccentrically located with respect to the axis of the shaft. The two valve stems 135 of the valves 133 and 134 are provided with connections 151 and 152, which are secured to said valve stems and which are drilled to receive the two pins 148 and 149. By means of this construction the two valves 133 and 134 may be simultaneously operated to open or close both the hot and cold water passageways.

The control valve 106 includes a rotatable valve member 153, which is preferably conical in form and which fits snugly within a conical bore 154 in valve housing 107. This valve member is constructed with a T-shaped passageway 155, having branches 156 and 157 in alignment with one another, and with a branch 158 at right angles to the branches 156 and 157. The cold water passageway 118 extends up to the bore 154. Two other passageways 161 and 162

are provided, which also extend up to the bore 154. Passageway 162 communicates with the passageway 119. Cold water may travel from the passageway 118 through branch 156 of the passageway 155 through branch 158 thereof, and into passageway 161 from which the same is led to the cold water sprays and the motor. At the same time hot water may flow from passageway 119 to the hot water sprays. When the valve member 153 is rotated clockwise through an angle of ninety degrees, passageway 118 is shut off and passageway 161 brought into communication with passageway 162 through the two branches 156 and 157 of passageway 155. With the parts so arranged hot water is led into all of the nozzles and also to the water motor. For manipulating the valve member 153, a handle 163 is provided which is directly attached to the same upon the exterior of the valve housing.

As previously stated, the pressure of the water furnished at the spray nozzles and motor is controlled through a constant pressure regulating valve mechanism, indicated in its entirety by the reference numeral 164. This valve mechanism includes a valve housing 165, formed with a flange 166 at one end thereof. The valve housing 165 is bolted to the valve housing 197 through bolts 167, which extend through the flange 166 and are threaded into a similar flange 168 formed on the housing 197. The construction of the valve mechanism 164 is best shown in Fig. 3. Valve housing 165 has two bores 171 and 172 therein. These bores communicate directly with the passageways 161 and 119 in the valve housing 197, whereby cold and hot water respectively are introduced into said bores when the valve mechanism 164 is opened. Within these bores are mounted for reciprocation two pistons 173 and 174. Valve housing 165 is provided with two bosses 176 and 177, which are formed with passageways 178 and 179. These passageways lead directly to the bores 171 and 172 and serve to direct the fluid consumed by the device to the proper outlets. The two pistons 173 and 174 within the bores 171 and 172 are constructed in identically the same manner and also function and operate in the same manner. For this reason only the piston 173 and its associated structure will be described in detail. Piston 173 is constructed at its lower end with a cavity 181. A port 182 extends through the wall of the piston and is adapted to bring the passageway 178 into communication with the cavity 181. Said cavity being open at the lower end, brings the port 182 into communication with the lower end of the bore 171, which is in communication with passageway 161. Through the piston 173 a chamber 193 is formed in bore 171 above said piston. This chamber is brought into communication with the passageway 178 through a bypass 194 formed in the housing 165. When the valve body 153 is in the position shown in Fig. 3, cold water is led into the regulating valve and discharged through port 182 into passageway 178, where it feeds the various outlets connected to said valve. The piston 173 is guided for movement within the bore through a pin 183 extending through the housing 165, which pin operates in a slot 184 in said piston. By means of this construction the piston is held from rotation and the movement of the piston at the end of its stroke is limited. The other end of the piston is provided with a socket 185, in which is seated a coil spring 186. This coil spring is seated at its other end against

a cap 187. Cap 187 is formed with a socket 188 in the center thereof and is provided at its edge with a flange 189, adapted to form a seat against which the upper end of the spring 186 may bear. A set screw 191 is threaded in the housing 165 and extends into and engages the cap 187 in the socket 188. A lock nut 192 is placed upon the set screw 191 and engages the outer surface of the housing 165 holding the set screw 191 in adjusted position. By manipulation of said set screw the pressure on the spring 186 may be varied so as to procure any desired regulation of pressure. Below the piston 173 is a stabilizing spring 286 which cushions the movement of the piston and causes the regulating device to act smoothly. The piston 174 previously referred to is constructed and controlled in the same manner as the piston 173 and regulates the pressure of hot water, which enters the cylinder 172 through the passageway 119.

The operation of the constant pressure regulating valve is as follows: Assume that the valve mechanism 164 is shut off. Spring 186 then urges the piston 173 downwardly until the pin 183 terminates the movement thereof. The opening through port 182 is then shut off. If now the valve mechanism 164 is turned on, the water is directed into the bore 171 and piston 173 is raised upwardly, which permits the water to flow into passageway 178. Water continues to flow in this passageway until a pressure is built up, which is transmitted by the bypass 194 to the chamber 193. This pressure of the water on this side of the piston together with the effort of the spring 86 tends to balance the pressure upon the underside of the piston through the water pressure in the water pipe. As the pressure in the passageway 178 varies, piston 173 moves up and down cutting off and on the water supply so as to maintain a constant pressure.

For the purpose of leading water to the various sprays, two flexible tubes 195 and 196 are employed which are connected by means of tube connections 197 and 198 to the two bosses 176 and 177 formed on the case 165. The tube 195 is directly connected to the mounting 276 and to nozzle 75 carried thereby. A branch tube 199 is also connected to the tube 195 and is connected by means of a tube connection 200 to a boss 201 formed on the part 57 of manifold 78 of the lower spray unit 76. This boss is so situated that tube 199 communicates with chamber 86 within the same. Tube 196 is similarly connected by means of a tube connection 300 to a boss 202, formed on the part 58 of said manifold by means of which said tube is brought into communication with the chamber 87 of said manifold. The two corresponding chambers of the upper manifold of spray unit 77 are connected to the chambers 86 and 87 by means of two vertically extending tubes 203 and 204, which extend along the upright 96 and are protected and guarded thereby. These tubes are connected to the manifold 78 and the manifold of the upper spray unit 77 in the same manner as the tubes 199 and 196. In this manner water is delivered from the lower spray unit to the upper spray unit, hot water being provided on the right hand side, and cold water on the left hand side.

The operation of the invention is as follows: In starting the device, the valve body 153 is left in the position shown in Fig. 3. As soon as the handle 163 is turned in the proper direction, both the valves 133 and 134 are opened, leading water

into the device. The cold water flows through the passageways 114, 116 and 118, through the branches 156 and 158 of passageway 155, through passageway 161, bore 171, cavity 181, port 182, passageway 178 and tube 195 to the motor nozzle 75. Water leaving this nozzle causes the wheel 51 to rotate, which sets in motion the train of gearing, causing the friction pinion 62 to rotate at a slow rate of speed. 5 Through the action of spring 69 this pinion is urged against the friction gear 74, which causes the rack B to rotate in a counter-clockwise direction as viewed in Fig. 2. Cold water at the same time passes through the tubes 199 and 203 10 and into the chambers 86 of the two spray units 76 and 77. The hot water passes through the passageway 115, passageway 117, passageway 119, into the bore 172, cavity 181, and port 182 of piston 174 and from there through the passageway 179 and tubes 196 and 204, to the chambers 87 of the spray units 76 and 77. This causes 15 sprays to be directed upwardly and downwardly from the nozzles attached to said units. If now glasses are placed upon the rack B in inverted 20 position, said glasses are caused to travel through the sprays and are washed both within and without.

Inasmuch as glasses are frequently desired for immediate use, it becomes desirable to cool the 30 same. Therefore the cold water sprays are used which chill the glasses before the same are removed from the rack. When the glasses appear opposite the opening in the housing A, the same may be again withdrawn. If the operator should 35 fail to remove the glasses, no particular harm is done, as the glasses merely go through the machine a second time and are further sprayed. When it is desired to wash the glasses solely with hot water, the handle 163 may be turned so that 40 the valve member 153 is arranged in a position at right angles to that shown in Fig. 3. Hot water is then directed to all of the nozzles and to the motor and the glasses washed exclusively by hot water.

45 Our invention is highly advantageous in that an extremely practical device is provided whereby the functioning of the various parts of a machine for washing drinking vessels may be positively and accurately controlled. With our invention 50 the proper pressure is maintained both for the cold and hot water so that the sprays operate with the desired amount of force to procure the best washing effect and so that the motor operates at a uniform rate of speed. By means of this construction, waste of water is prevented. The motor is designed for relatively low pressure 55 so that the machine operates under pressures such as are available with ordinary municipal water systems. Both the hot and cold water are 60 shut off by a single valve so that the operator has merely one valve to consider in starting and stopping the machine. With our invention hot or cold water as desired may be delivered to certain 65 of the sprays, whereby more rapid washing of the drinking vessels can be procured where cooling is not required. This also permits of rapidly running the drinking vessels through the machine. The parts of our invention are arranged 70 in a manner to be extremely convenient for manipulation. By the disposition of the parts all of the operating parts are disposed beneath the rack where the same are out of the way.

Changes in the specific form of our invention, 75 as herein disclosed, may be made within the

scope of what is claimed without departing from the spirit of our invention.

Having described our invention, what we claim as new and desire to protect by Letters Patent is:

1. In a machine for washing drinking vessels, 5 a support, a rack rotatably mounted on said support, a water motor for driving said rack, hot and cold water sprays for washing vessels carried by said rack, a cold water conduit connected to the cold water sprays and to said motor, a hot water conduit connected to said hot water sprays and separate regulating valves in each of said conduits for independently controlling the pressures of the hot and cold water and a valve structure for simultaneously shutting off the flow of water 10 in said conduits. 15

2. In a machine for washing drinking vessels, 20 a support a rack for drinking vessels movably mounted on said support, cold water sprays, hot water sprays, said sprays being positioned adjacent said rack to discharge water upon said drinking vessels, a water motor positioned adjacent said rack and driving the same, a cold water conduit for feeding the cold water sprays and water motor, a hot water conduit for feeding the hot 25 water sprays, separate valves in said conduits and separate pressure controlled means for operating said valves.

3. In a machine for washing drinking vessels, 30 a housing, a cold water spray within said housing, a hot water spray within said housing, a rack for supporting drinking vessels disposed within said housing and movable past said sprays, a control valve within said housing having a body provided with a cold water passageway and a hot 35 water passageway, a conduit connecting said cold water spray with said cold water passageway, a conduit connecting said hot water spray with said hot water passageway, said valve including a movable valve member having a ported chamber, 40 said cold water passageway communicating with said ported chamber, and an auxiliary passageway leading from said hot water passageway communicating with said ported chamber, said valve member in one position causing hot water 45 to be delivered to the hot water conduit and cold water to be delivered to the cold water conduit and in another position causing hot water to be delivered to both conduits. 50

4. In a machine for washing drinking vessels, 55 a tray, a rack rotatably mounted above said tray, a hot water spray and a cold water spray, said sprays being positioned to wash vessels carried by the rack, a water motor carried by the tray for driving said rack, hot and cold water supply 60 conduits, a casting carried by said tray and having two valves therein connected to said conduits for shutting off the flow of hot and cold water, a control valve for controlling the flow of hot water to said motor and certain of said sprays, said 65 control valve being attached to said shut off valves and communicating with said shut off valves, two constant pressure regulating valves connected to and carried by said control valve, one of said valves communicating with said cold water supply and the other with the hot water supply, a conduit connecting said cold water constant pressure regulating valve with said cold water spray and motor and another conduit connecting said hot water constant pressure regulating valve with 70 said hot water spray, said valves delivering water under predetermined pressure to said motor and sprays.

5. In a machine for washing drinking vessels, 75 a support, a rack rotatably mounted on said sup-

port, a water motor for driving said rack, a hot water spray and a cold water spray for washing vessels carried by said rack, hot and cold water conduits furnishing hot and cold water to the machine, two shut off valves in said hot and cold water conduits, a casting connected to said valves, said casting having hot and cold passageways therein, a control valve in said casting controlling the flow through the cold water passageway, constant pressure regulating valves communicating with both of said passageways, said control valve having passageways operating in conjunction with the passageways in said casting

and adapted in one position to direct hot water to one of said constant pressure regulating valves and cold water to the other and in its other position to direct hot water to both of said constant pressure regulating valves, a conduit leading from the hot water constant pressure regulating valve to one of said sprays and another conduit leading from said cold water constant pressure regulating valve to said water motor and to the other of said sprays.

WALTER F. OHME.
RAY C. STEPHAN.

CERTIFICATE OF CORRECTION.

Patent No. 2,170,307.

August 22, 1939.

WALTER F. OHME, ET AL.

It is hereby certified that error appears in the printed specification of the above numbered patent requiring correction as follows: Page 5, second column, line 59, claim 4, strike out the word "hot"; page 6, first column, line 7, claim 5, after "cold" insert water; and that the said Letters Patent should be read with this correction therein that the same may conform to the record of the case in the Patent Office.

Signed and sealed this 3rd day of October, A. D. 1939.

(Seal)

Henry Van Arsdale,
Acting Commissioner of Patents
